DESIGN FOR A LIGHTING FIXTURE GLOBE

Samuel S. Dauman, New York, N. Y.

Application April 10, 1936, Serial No. 62,044

Term of patent 14 years

To all whom it may concern:

Be it known that I, Samuel S. Dauman, a citizen of the United States of America, and a resident of the Borough of Manhattan, city, county, and State of New York, have invented a new, original, and ornamental Design for a Lighting Fixture Globe, of which the following is a specification, reference being had to the accompanying drawing forming a part thereof.

Fig. 1 is a side elevational view of the lighting fixture globe showing my new design; and Fig. 2 is an inverted plan view thereof.

I claim:

The ornamental design for a lighting fixture globe substantially as shown.

SAMUEL S. DAUMAN.
